D. L. McCORKINDALE

DRIER FELT STRETCHER

Filed June 23, 1923

FIG. 1

FIG. 2

UNITED STATES PATENT OFFICE.

DUNCAN L. McCORKINDALE, OF HOLYOKE, MASSACHUSETTS.

DRIER-FELT STRETCHER.

Application filed June 23, 1923. Serial No. 647,318.

To all whom it may concern:

Be it known that I, DUNCAN L. McCORKINDALE, a citizen of the United States of America, and a resident of Holyoke, in the 5 county of Hampden and State of Massachusetts, have invented a new and useful Drier-Felt Stretcher, of which the following is a specification.

My invention relates to improvements in 10 automatic drier-felt stretchers for paper-making machines, and consists essentially of suitable guide members attached to opposite sides of the frame of a paper-making machine, guide blocks slidably arranged in 15 said members and forming bearings for the shaft of a stretcher roll, a suitably journaled shaft having winding drums and a ratchet-wheel secured thereon, cables or chains attached to said blocks and drums, and a 20 weighted lever loosely mounted on said last-named shaft, and provided with a spring-pressed detent or dog to engage said ratchet-wheel, together with such other parts and members as may be necessary or desirable in 25 order to render the stretcher serviceable in every respect, all as hereinafter set forth.

The drier felt of a paper-making machine expands and contracts more or less under changing weather conditions, and stretches 30 under the stress incident to use, but in spite of such variations said felt must be kept taut at all times, and the primary object of my invention is to provide comparatively simple and inexpensive means or mechanism for 35 exerting a constant pressure or tension on the felt, which tension is sufficient to keep the felt taut by taking up the slack therein, and of a nature that yields whenever the felt contracts, such mechanism being applicable to 40 practically any paper-making machine.

A further object is to furnish a stretcher of this character with readily adjustable means, whereby the stretcher is rendered capable of taking care of an amount of slack 45 in the drier felt in excess of that which said stretcher otherwise would be capable of taking care of, or, in other words, to furnish the stretcher with take-up or resetting means.

My stretcher performs its function without 50 injury to the felt.

Other objects and advantages will appear in the course of the following description.

I attain the objects and secure the advantages of my invention by the means illustrated in the accompanying drawings, in 55 which—

Figure 1 is a side elevation of an intermediate sectional part of a paper-making machine equipped with a drier-felt stretcher which embodies a practical form of my invention, a fragmentary portion of the machine frame being broken out to disclose to better advantage certain parts of said stretcher; Fig. 2, a cross section through said sectional part of said machine and said 60 stretcher looking toward the right in Fig. 1, and, Fig. 3, an enlarged top plan of one of the guide elements of the stretcher.

Similar reference characters designate 65 similar parts throughout the several views.

The ordinary type of paper-making machine comprises a long frame carrying a series of drier drums, sets of felt-guide rolls and paper-carrying rolls associated with each of such drums, and a drier felt which 70 passes over said felt-guide rolls and under said drums, all constructed, arranged, and operating in the usual and well-known manner. Of such a machine I have shown fragmentary portions of the sides of the frame, 75 generally designated by the numeral 1, two drier drums 2, two pairs of felt-guide rolls 3, two pairs of paper-carrying rolls 4, and a portion of a drier felt 5. The felt 5 passes over the left-hand roll 3 in the left-hand 80 pair, down under the associated drum 2, up over the other roll 3 in such pair, forward to the left-hand roll 3 in the right-hand pair, down under the right-hand drum 2, up over the right-hand roll 3 in said last-named pair, 85 and forward again, and my tightener is applied to the portion of said felt which is between the two intermediate of the four rolls 90 3. My invention includes a stretcher roll 6, and such roll is applied to the aforesaid portion of the felt 5 from above, and such portion is usually drawn downwardly by said roll to a greater or less extent between the two rolls 3 of which mention has just been 95 made. In other words, the slack in the felt 5 is taken care of by my stretcher at the place designated above. It may be noted in passing that the paper, which is carried forward with the assistance of the felt 5, spans the 100

space where the stretching or tightening takes place, because said paper is there carried on the two intermediate of the four rolls 4. The roll 6 is, of course, parallel with the other rolls.

The tightener roll 6 is mounted on a shaft 7, and such shaft is journaled in blocks 8—8. The blocks 8 must be slidingly supported vertically, and to this end suitable vertical guides are provided. These guides, which are fastened to or might be integral with the sides of the frame, naturally will vary more or less in size and shape to meet the conditions and be capable of attachment to different styles of frames, but in the main such guides are generally similar. The guides here shown and described are designated by the numeral 9. Each guide 9 has at the base two oppositely-directed arms or wings 10, and above said wings two oppositely-directed arms or wings 11, the upper wings being shorter than the lower wings, and all of said wings projecting beyond the outer face of the main portion of the guide in order to provide space or clearance between said main portion and the side of the frame 1 to which the wings are directly attached, and between the wings in each pair, for the accommodation of a vertical chain or cable 13. The cable 13 is attached at the top to a horizontal bolt 14 that passes through a pair of ears or lugs 12 on the outer side of each block 8, such lugs projecting horizontally from such block. The wings 10 of each guide 9 are bolted at 15—15 to one side of the frame 1, and the wings 11 are bolted at 16—16 to said side at points above those where are bolted said wings 10. There is a vertical slot 17 in each guide 9 for one of the blocks 8, and extending inwardly from the sides of such slot are two vertical ribs 18 which are received in corresponding grooves in the block in said slot, as best shown in Fig. 3. Thus it is seen that the blocks 8 can move freely up and down in the slots 17 without becoming displaced.

The bolts 14 are parallel with the outer sides of the blocks 8, and a nut 19 may be provided to hold each of said bolts in place in the lugs 12.

A horizontal winding shaft 20 is journaled in bearings 21—21 which are secured to the floor upon which the frame 1 rests, one of said bearings being inside of what may be termed the back side of said frame, and the other of said bearings being inside of what may be termed the front side of said frame. Two winding drums 22 are secured on the shaft 20 and located by said shaft, which latter is parallel with the drums 2 and rolls 3 and 4, with the right-hand ends of the horizontal diameters of said winding drums in the vertical plane of the axis of the tightener roll 6, as clearly shown in Fig. 1. The rear drum 22 is be-

hind the rear bearing 21 and the front drum 22 is behind the front bearing 21, and both of said drums are inside of the sides of the frame, as are the blocks 8 and the bolts 14. The cables 13 pass from the bolts 14 downwardly, between the sides of the frame and the guides 9, and between those portions of the wings 10 and 11 that extend beyond the outer faces of the body portions of said guides, to the drums 22, upon which latter said cables are wound and to which they are securely attached.

The forward terminal of the shaft 20 extends beyond the front bearing 21, and loosely mounted on said terminal is a lever 23. The lever 23 is bifurcated at the terminal which is mounted on the shaft 20, and secured to said shaft between the fork arms of said lever is a ratchet-wheel 24. The lever 23 extends to the right from the shaft 20, and a counterweight 25 is slidingly arranged on said lever at the free terminal thereof. The upper edge of the lever 23 may be serrated, as at 26, and the top of the passage through the counterweight 25 which receives said lever may be similarly serrated, if desired, in order to provide means whereby said counterweight is prevented from accidentally slipping or moving on said lever after the former has been adjusted on the latter. The aforesaid passage in the counterweight 25 is of sufficient depth to permit said counterweight to be raised without the lever 23 to the extent required to disengage the serrated parts and permit the counterweight to be adjusted on the lever. The power exerted by the lever 23 is, of course, increased by moving the counterweight 25 nearer to the free end of said lever, and decreased by moving said counterweight farther away from such end.

A detent or dog 27 is pivotally connected at 28 to the lever 23 between the fork arms thereof, and said dog at the free end engages the teeth of the ratchet-wheel 24. A spring 29 is arranged between the fork arms of the lever 23 to bear against the bottom edge of the dog 27, for the purpose presently to be explained.

The extreme forward end of the shaft 20, in front of the lever 23, is made angular in cross-section to form a head 30 which is adapted to be received in or engaged by a wrench.

The dog 27 is so constructed, arranged, and located that said dog at its free end fills the space between two of the teeth of the ratchet-wheel 24, with the top of such end in approximately the plane which connects the axes of the shaft 20 and the pivot 28, consequently there is normally no independent movement between said dog and ratchet-wheel and the two latter lock the lever 23 to said shaft. The ratchet-wheel and dog provide, however, for readjustment of the lever

23 on the shaft 20, or movement of said lever on said shaft while the latter is held stationary. Thus, by applying a wrench to the head 30 and holding the shaft 20 against 5 rotation, the lever 23 can be swung upwardly on said shaft, the dog 27 then snapping past the teeth of the ratchet-wheel 24 as said dog is carried upwardly with said lever, the spring 29 yielding for this purpose, while at 10 the same time preventing the dog from swinging downwardly to an extent that would completely disengage it from said ratchet-wheel. After the required adjustment has been made the dog 27 is left in 15 engagement with different teeth from those with which it was previously engaged, unless the adjustment involved a complete revolution of the ratchet-wheel. In making the adjustment, the lever 23 is swung upwardly while the shaft 20 is held stationary, then said shaft is released and said lever swung downwardly, with the result that a 20 partial revolution is imparted to said shaft and the drums 22, and more of the cables 25 13 are wound on said drums, thus shortening said cables and rendering the stretcher capable once more of normal action.

In practice, the weighted lever 23 tends 30 constantly to actuate the shaft 20 in the direction to wind the cables 13 on the drums 22 and thus draw down the blocks 8 and with them the roll 6. The force thus exerted on the roll 6 is applied through said roll to the felt 5, which travels beneath said roll, and 35 thus takes the slack out of said felt and keeps the same taut. In the event the felt 5 contracts, it draws up the roll 6 against the resistance offered by the weighted lever 23 and the intervening parts and members.

40 If there be too much slack in the felt 5 and the lever 23 swings downwardly too far or until the free end thereof touches the floor, the shaft 20 is held against rotation by its head 30, and said lever is swung upwardly on said shaft to cause the dog 27 to 45 make a fresh engagement with the ratchet-wheel 24, and then said lever is rocked downwardly again, thus winding more of the cables 13 onto the drums 22, as previously 50 explained, the operation being repeated as often as may be necessary in order to take care of the slack which would occur in the cables 13 and felt 5 if said lever were permitted to touch the floor. Ordinarily the 55 parts are so adjusted that the lever 23 is disposed in an approximately horizontal position.

The ratchet-wheel 24 and the dog 27 constitute locking means between the shaft 20 60 and the lever 23 for the latter.

This stretcher may be practically used in inverted position, but in such case the weight of the stretcher roll and other parts is lost as an effective medium applied to the felt, 65 and the counterweight must be heavy enough

to carry such weight as well as to stretch the felt.

More or less change in the shape, size, construction, and arrangement of some or all of the parts of this stretcher, in addition to 70 those hereinbefore specifically pointed out, may be made without departing from the spirit of my invention or exceeding the scope of what is claimed.

I am aware that various counterweighted appliances have been previously employed for stretching drier felts, and do not, therefore, seek to claim broadly such an appliance. 75

What I do claim as my invention, and desire to secure by Letters Patent, is—

1. The combination, in a drier-felt stretcher, with the frame and drier felt of a paper-making machine, said frame being provided with fixed and movable guiding means, of a stretcher roll for said felt, said roll being journaled in the movable guiding means, a suitably journaled shaft, winding drums secured to said shaft, flexible members between said movable guiding means and said drums, and a weighted lever loosely mounted on and locked to said shaft. 80

2. The combination, in a drier-felt stretcher, with the frame and drier felt of a paper-making machine, of removable guides attached to said frame, bearing members slidably connected with said guides, a stretcher roll for said felt having a shaft which is journaled in said bearing members, a suitably journaled winding shaft, drums secured to said shaft, flexible members attached to said members and to said drums, and a weighted lever mounted on and locked to said winding shaft. 95

3. The combination, in a drier-felt stretcher, with the frame and drier felt of a paper-making machine, of removable slotted guides attached to said frame, blocks slidably arranged in the slots in said guides, a stretcher roll for said felt having a shaft which is journaled in said blocks, a suitably journaled winding shaft, drums secured to said winding shaft, flexible members attached to said blocks and to said drums and a weighted lever mounted on and locked to said winding shaft. 100

4. The combination, in a drier-felt stretcher, with the frame and drier felt of a paper-making machine, of guides having wings which are bolted to the sides of said frame, said wings being so constructed that the body portions of said guides are remotely supported relative to said frame sides, bearing members slidably connected with said guides, and provided with attaching means in the space between said body portions and said sides, a stretcher roll for said felt having a shaft which is journaled in said bearing members, a suitably journaled winding shaft, drums secured to said winding shaft, 110 115 120 125 130

ing shaft, flexible members between said bearing members and said drums, and a weighted lever locked to said winding shaft.

5. The combination, in a drier-felt stretcher, with the frame and drier felt of a paper-making machine, of slotted guides having wings which are bolted to the sides of said frame, said wings being so constructed that the main body portions of said 10 guides are remotely supported relative to said frame sides, blocks slidably arranged in the slots in said guides, and provided with lugs which extend into the spaces between said body portions and said frame 15 sides, bolts carried by said lugs, a stretcher roll for the felt having a shaft journaled in said blocks, a suitably journaled winding shaft, drums secured to said shaft, flexible members attached to said bolts and to said drums, and a weighted lever locked to said winding shaft.

6. The combination, in a drier-felt stretcher, with the frame and drier felt of a paper-making machine, said frame being provided with fixed and movable guiding means, of a stretcher roll for said felt having a shaft journaled in said movable guiding means, a suitably journaled winding shaft, drums secured to said shaft, flexible 30 members attached to said movable guiding means and to said drums, a weighted lever mounted on said winding shaft, and adjustable locking means between said lever and said winding shaft.

35. 7. The combination, in a drier-felt stretcher, with the frame and drier felt of a paper-making machine, said frame being provided with fixed and movable guiding means, of a stretcher roll having a shaft journaled in said movable guiding means, a suitably journaled winding shaft, drums and a ratchet-wheel secured to said winding shaft, flexible members attached to said movable guiding means and to said drums, 40 a weighted lever loosely mounted on said 45 winding shaft, and a dog pivotally con-

nected with said lever and adapted to engage said ratchet-wheel, the construction and arrangement of parts being such that normally said dog locks said lever to said 50 winding shaft, through the medium of said ratchet-wheel, but is capable, when said winding shaft is held against rotation and said lever is swung upwardly, of passing over the ratchet-wheel teeth and making a 55 fresh engagement therewith.

8. A drier-felt stretcher comprising guides which are attachable to the frame of a paper-making machine, bearing members for sliding connection with said guides, a stretcher roll for the felt of such machine, said roll being mounted on a shaft which is designed to be journaled in said bearing members, a winding shaft and bearings therefor, drums secured to said winding shaft, flexible members adapted to be attached to said bearing members and to said drums, a weighted lever mounted on said winding shaft, and adjustable means to lock said lever to said winding shaft.

70 9. A drier-felt stretcher comprising guides which are attachable to the frame of a paper-making machine, bearing members for sliding connection with said guides, a stretcher roll for the felt of such machine, said roll being mounted on a shaft which is designed to be journaled in said bearing members, a winding shaft and bearings therefor, drums and a ratchet-wheel secured to said winding shaft, a weighted lever 75 loosely mounted on said winding shaft, and a dog pivotally connected with said lever and adapted to engage said ratchet-wheel, said dog normally locking said lever to said winding shaft, through the medium of said ratchet-wheel, but capable of being moved to make a new engagement with said ratchet-wheel.
